UNITED STATES PATENT OFFICE.

WILLIAM F. NEUBECK, OF BROOKLYN, NEW YORK.

DESIGN FOR A CASING FOR SIGNAL LIGHT.

Application filed March 9, 1925. Serial No. 12,643. Term of patent 14 years.

To all whom it may concern:

Be it known that I, WILLIAM F. NEUBECK, a citizen of the United States, residing at Brooklyn, in the county of Queens and State of New York, have invented a new, original, and ornamental Design for a Casing for Signal Light, of which the following is a specification, reference being had to the accompanying drawing, forming part thereof.

Figure 1 is a rear elevation.

Figure 2 is a top plan view.

Figure 3 is an end view.

I claim:

The ornamental design for a casing for signal light, as shown.

WILLIAM F. NEUBECK.
